(57) **CLAIM**

The ornamental design for a lighting fixture, as shown and described.

DESCRIPTION

FIG. 1 is an isometric view of a first embodiment of the lighting fixture of the present invention shown from the bottom and the front side;

FIG. 2 is a bottom plan view of the lighting fixture illustrated in FIG. 1;

FIG. 3 is a top plan view of the lighting fixture illustrated in FIGS. 1 and 2;

FIG. 4 is a front isometric view of the lighting fixture illustrated in FIGS. 1 through 3;

FIG. 5 is a rear isometric view of the lighting fixture illustrated in FIGS. 1 through 4;

FIG. 6 is a right side isometric view of the lighting fixture illustrated in FIGS. 1 through 5, the left side being a mirror image thereof;

FIG. 7 is an isometric view of a second embodiment of the lighting fixture of the present invention shown from the bottom and the front side;

FIG. 8 is a bottom plan view of the lighting fixture illustrated in FIG. 7;

FIG. 9 is a top plan view of the lighting fixture illustrated in FIGS. 7 and 8;

FIG. 10 is a front isometric view of the lighting fixture illustrated in FIGS. 7 through 9;

FIG. 11 is a rear isometric view of the lighting fixture illustrated in FIGS. 7 through 10;

FIG. 12 is a right side isometric view of the lighting fixture illustrated in FIGS. 7 through 11, the left side being a mirror image thereof;

FIG. 13 is an isometric view of a third embodiment of the lighting fixture of the present invention shown from the bottom and the front side;

FIG. 14 is a bottom plan view of the lighting fixture illustrated in FIG. 13;

FIG. 15 is a top plan view of the lighting fixture illustrated in FIGS. 13 and 14;

FIG. 16 is a front isometric view of the lighting fixture illustrated in FIGS. 13 through 15;

FIG. 17 is a rear isometric view of the lighting fixture illustrated in FIGS. 13 through 16;

FIG. 18 is a right side isometric view of the lighting fixture illustrated in FIGS. 13 through 17, the left side being a mirror image thereof;

FIG. 19 is an isometric view of a fourth embodiment of the lighting fixture of the present invention shown from the bottom and the front side;

FIG. 20 is a bottom plan view of the lighting fixture illustrated in FIG. 19;

FIG. 21 is a top plan view of the lighting fixture illustrated in FIGS. 19 and 20;

FIG. 22 is a front isometric view of the lighting fixture illustrated in FIGS. 19 through 21;

FIG. 23 is a rear isometric view of the lighting fixture illustrated in FIGS. 19 through 22; and,

FIG. 24 is a right side isometric view of the lighting fixture illustrated in FIGS. 19 through 23, the left side being a mirror image thereof.

The broken lines in the drawing form no part of the claimed design.
